UNITED STATES PATENT OFFICE.

CHARLES E. BENTLEY, OF NEW YORK, N. Y.

DESIGN FOR A BOTTLE.

SPECIFICATION forming part of Design No. 20,027, dated July 15, 1890.

Application filed June 3, 1890. Serial No. 354,137. Term of patent 7 years.

To all whom it may concern:

Be it known that I, CHARLES E. BENTLEY, a citizen of the United States, residing at the city of New York, in the county and State of New York, have invented and produced a new and original Design for a Bottle, of which the following is a specification, reference being had to the accompanying drawing, forming part thereof, and which is a side elevation of the bottle and fully illustrates the design.

The leading feature of my design for a bottle or dressing-case ornament consists, mainly, in the peculiar configuration of the lower body portion, which is surmounted by a comparatively long neck or stem.

The body A of the bottle or ornament has the appearance of being turned in a lathe in circular outline, and is longest in diameter near the base or bottom, where it is formed with a substantially vertical marginal portion 1, provided with a circumferential groove

or concavity 2. From the upper edge of the part 1 the sides of the bottle-body sweep inward and upward in concaved lines 3, which merge into the neck or stem a, which may be straight or cylindrical for its whole length, but is preferably enlarged a little toward its top, as shown. From the lower edge of the vertical marginal portion 1 the sides of the bottle-body curve inward rather sharply and then downward in concaved lines 4 to the base or bottom 5 of the bottle.

An ordinary cut-glass stopper is shown in the neck or stem of the bottle.

I claim as my invention—

The design for a bottle, substantially as herein shown and described.

CHARLES E. BENTLEY.
